(57) CLAIM

The ornamental design for a combined shopping cart corral with advertising panels, as shown and described.

DESCRIPTION

FIG. 1 is a perspective view of the combined shopping cart corral with advertising panels;

FIG. 2 is a right side view thereof;

FIG. 3 is a left side view thereof;

FIG. 4 is a front view thereof;

FIG. 5 is a rear view thereof; and,

FIG. 6 is a top view thereof.

The broken lines in the drawings of the shopping cart corral in FIGS. 1-6 are for the purpose of illustrating an environment only and form no part of the claimed design.

1 Claim, 5 Drawing Sheets---
